UNITED STATES PATENT OFFICE.

JOHN J. CAIN, OF BAYONNE, NEW JERSEY.

BOILER.

1,263,851.

Specification of Letters Patent.

Patented Apr. 23, 1918.

Application filed March 27, 1917. Serial No. 157,673.

To all whom it may concern:

Be it known that I, JOHN J. CAIN, residing at Bayonne, county of Hudson, State of New Jersey, have invented new and useful Improvements in Boilers, of which the following is a specification.

This invention pertains to that class of boilers composed of sections transversely arranged and connected together with communicating passages between them.

The object of this invention is to simplify the construction of such boilers, to strengthen the sections against expansion and contraction effects and to increase the efficiency by fully utilizing all parts of the sections as heating surfaces. To this end the sections are formed with their adjacent sides as continuous surfaces and their interiors are formed by a one-piece core, said adjacent surfaces being horizontally corrugated and spaced apart to provide parallel sinuous passages for the adequate flow of the products of combustion from the furnace in upward and lateral directions, which from its lateral flow passes around the side edges of the sections. The sections have at the lower parts of their sides supporting legs and the spaces between these legs constitute the fire box. The lower parts of the legs and the central upper parts of the sections are wider than the corrugated body portions, they are formed to contact and determine the width of the passages between the main portions, they are provided with connecting nipples, or other suitable means, for affording communication between the interiors of all of the sections. Flues, longitudinally the boiler, pass through the water, or water and steam, spaces of the sections, being formed by short pipe pieces cast integral with the sections and arranged to abut in the gas passages between the sections. These flues open into a connecting chamber in the front wall of the boiler; one, the discharge flue passes through the back wall and the open ends of the other flues face toward the front side of the back wall.

To direct the flow of gases around the side edges and over the tops of the sections toward the back wall casings are provided, preferably composed of insulating material. A suitable construction for this purpose being fire bricks formed with projections to act as baffle plates, sheet asbestos on the outer side of the fire bricks and a sheet

metal casing or container surrounding the asbestos and adequately secured to the boiler.

These features with other details of construction will now be fully described by reference had to the accompanying drawings, in which:

Figure 1, is a half full view and a half sectional view of the front wall of a boiler embodying this invention.

Fig. 2, an elevation of one of the component sections of the boiler, showing one-half full face view and one-half in section.

Fig. 3, shows different views of assembled sections; 5 being a full edge view of a section; 6, a central sectional view on line 6, 6, Fig. 2; 7 another vertical section on line 7, 7, Fig. 2, and 8, an edge view of the back wall; and:

Fig. 4, a plan sectional view of two of the component sections, taken on line 4, 4, Figs. 1 and 2.

All of the sections transversely arranged between the front and back walls and constituting practically the whole of the boiler are alike. They may be shaped as shown in Fig. 2, with the side edges 9, vertical, but their general contour may be varied to suit different kinds and styles of boilers. Each section has a large central opening 10, at its lower part, preferably arch shaped, which in the assembled sections form the fire chamber. The adjacent faces of the widened portions 11, contact and their surfaces at the inner sides of the legs form continuous side walls for the fire box, so that the fuel will be properly contained therein. The top surfaces of the parts 11, in the spaces between the faces of adjacent sections, incline downwardly toward the fire at an angle sufficient to prevent pieces of coal and ashes lodging thereon, as shown in Figs. 2 and 3. Said inclined surfaces constitute the bottoms of the side flues and will direct the gases from the furnace upwardly through the flues and around the outer edges of the sections. The portions at the sides of these openings form the supporting legs and lower ends 11, are wider than their main portions, as is also a portion 12, at the central part of the upper edge. The faces of these widened parts are in parallel planes which also include the projecting edges of short pieces of pipe forming flues 13, and 14, thus facilitating the necessary tooling of these faces to insure the proper

seating together of them when the sections are assembled. The excess of these widened parts over that of the main portions determine the width of the passages for the products of combustion between the sections. The sections are, of course, hollow and are constructed with all their parts integral, their interiors being formed by a one-piece core. This provides a very simple construction, as will be seen from an inspection of Fig. 2. The whole of the narrow main portions of the sections are corrugated in a horizontal direction, that is the straight lines of the corrugations run laterally, in such manner that the spaces 15, between adjacent sections are parallel in both directions and sinuous in a vertical direction. This formation while adding greatly to their strength against expansion and contraction also increases the vertical length of the flues and consequently adds to their heating surfaces. The side edges 9, are preferably rounded, as may also the upper edges 16 and the edges in the fire box. All parts of the sinuous flues 15, are of uniform width, their corrugated walls being parallel, thus insuring steady uniform flows of the gases in both vertical and horizontal directions and uniformity in heating effects on all parts of the sections.

The front 17, is also cast hollow and has formed in it a chamber 18, into which the front ends of the flues 13, and 14 open to afford communication between them at this end of the boiler. The rear end of the flue 14, passes through the back wall 8, and is connected to the discharge pipe or chimney, as at 19, Fig. 3. The sections are suitably clamped together; rods or bolts and nuts 20, may be used for this purpose, located as shown and extending through lugs 21, formed on the edges of the front and back walls. Tight joints may be made between the wide parts 11 and 12, and the ends of the short pieces of pipe forming the flues 13 and 14, by the application thereto of a suitable cement; it is preferred however to provide a mechanical connection between the interiors of the sections and the front and back walls, as for instance by means of ordinary push nipples 22.

The water supply or return water may enter the boiler at the central part of the back wall, as at 23, and the hot water when the boiler is used in a hot water system, or steam, when the boiler is used in a steam system, passes from a pipe opening 24, formed in the top of a section. This opening may be formed in all of the sections, to assist in holding the core during the casting process, and those not required for water or steam discharge be suitably plugged.

The sides and top edges of the section are covered by a casing, to direct the horizontal

and vertical flow of the gases from the furnace fire box 10, through the spaces 15, longitudinally toward the back wall 8. A suitable construction for this casing is shown, consisting of fire bricks 25, which 70 may have lateral projections 26, suitably perforated if necessary, to act as baffle plates, a sheet of insulating material 27, as asbestos, arranged against the outer side of the fire bricks and a sheet metal container 75 28, suitably secured to the boiler by angle pieces 29, and straps 30.

Any desired number of sections may be assembled to form different sizes of boilers, and according to the sizes of the sections. 80 The last section, or one next the back wall 8, may be made without the opening 10, it then becoming the back of the furnace, causing the direct rearward flow of the gases from the furnace to pass around its 85 edges and between its rear face and the back wall 8.

Baffle plates or blocks 31, may be placed as desired in various parts of the passages 15, to adequately retard the flow of the gases 90 therethrough; said baffles being held in set positions by the reverse curvatures of the passages.

32, designates the foundation of the boiler on which the various sections rest, and which forms the ash pit 33; 35, the ash pit door; 36, the fire box door; 37, the door covering the clinker discharge or slicing opening, 38, and 39, covers for closing the chamber 18, in the front and for cleaning 100 the flues 13 and 14; and 40, the grate.

I claim:

1. A boiler, comprising transverse sections provided with side supporting legs having at their lower parts contacting wide 105 portions lengthwise the boiler, the openings between the legs of each section forming the fire chamber and the inner sides of the wide portions constituting continuous side walls for the fire box at the lower part of 110 the chamber, the sections above the wide lower portions of the legs being spaced apart to provide continuous lateral passages from the fire chamber to the top and sides of the boiler, a back wall and a front 115 wall, a grate located in the fire box between its continuous side walls, casings at the sides of the boiler inclosing the side edges of the sections and affording passages lengthwise the boiler to direct the gases from the spaces 120 between the sections to the back wall and flues affording communication between the space at the front of the back wall and the outside of the boiler.

2. A boiler, comprising transverse sec- 125 tions provided with side supporting legs having at their lower parts contacting wide portions lengthwise the boiler, the open- ings between the legs of each section form- 130 ing the fire chamber and the inner sides of

the wide portions constituting continuous side walls for the fire box at the lower part of the chamber, the sections above the wide lower portions of the legs being spaced 5 apart to provide continuous lateral passages from the fire chamber to the top and sides of the boiler, connecting passages between the interiors of the sections at the lower parts of the legs and at the central 10 upper parts of the sections, a grate located in the fire box between its continuous side walls, a back wall and a front wall, casings at the sides and the top of the boiler inclosing the side and top edges of the sections 15 and affording passages lengthwise the boiler to direct the gases from the spaces between the sections to the back wall and flues affording communication between the front of the back wall and the outside of 20 the boiler.

3. A boiler, comprising horizontally corrugated transverse sections provided with side supporting legs having at their lower parts contacting wide portions lengthwise 25 of the boiler, the openings between the legs of each section forming the fire chamber and the inner sides of the wide portions constituting continuous side walls for the fire box at the lower part of the chamber, the sections above the wide portions of the legs being spaced apart to provide continuous lateral passages from the fire chamber 30 to the sides of the boiler, a grate located in the fire box between its continuous side walls, the upper surfaces of the wide portions of the legs in the spaces between the legs being inclined downwardly toward the grate, a back wall and a front wall, casings at the sides of the boiler inclosing the side 35 edges of the sections affording side passages lengthwise the boiler from the spaces between the sections to the back wall and flues affording communication between the space 40 in front of the back wall and the outside of the boiler.

4. A boiler, comprising transverse sections formed with side supporting legs and spaced apart to provide continuous lateral passages from the fire chamber in the central lower parts of the sections formed by the openings between the legs of each section to the top and sides of the boiler, a front wall a short distance from the fore-

most section, a back wall a short distance from the rearmost section, continuous flues 55 passing lengthwise the boiler composed of short sections of pipe extending through the sections and projecting from their adjacent faces with their ends abutting, said short sections of pipe being integral with 60 the sections of the boiler, a chamber in the front wall into which all of the flues open, one of the flues extending rearwardly through the back wall and the rear ends of the others opening into the space between 65 the rearmost boiler section and the back wall.

5. A boiler, comprising transverse sections provided with supporting legs, the inner sides of the legs forming the side walls 70 of the fire chamber, said sections being spaced apart to provide continuous passages, between their adjacent faces, for the products of combustion to pass to the top and to the sides of the boiler, a front wall 75 and a back wall, flues extending through the sections and the spaces between the sections with their forward ends in communication at the front wall, the rear end of one of them extending through the back wall and the open rear ends of the others facing the back wall, passages at the top and sides of the boiler, lengthwise thereof, extending to the back wall and into which all of the 80 passages between the sections open. 85

6. A boiler, comprising transverse sections spaced apart to provide continuous passages, between their adjacent faces, for the products of combustion to pass to the top and to the sides of the boiler and a 90 casing at the sides of the boiler at a distance from the side edges of the sections and affording at each side of the boiler a lengthwise passage to its rear end, said casing consisting of fire bricks having inner lateral 95 projections adapted to act as baffles, an outside sheet metal container secured to the boiler and sheet insulating material located between the fire bricks and the sheet metal container. 100

Signed at New York, county and State of New York, this 22nd day of March, 1917.
